his Attorney.

UNITED STATES PATENT OFFICE.

HARRY BARGMAN, OF LOS ANGELES, CALIFORNIA.

FUSE-IGNITER.

945,076.

Specification of Letters Patent. Patented Jan. 4, 1910.

Application filed June 14, 1909. Serial No. 501,996.

To all whom it may concern:

Be it known that I, HARRY BARGMAN, a citizen of Russia, residing at Los Angeles, in the county of Los Angeles and State of California, have invented certain new and useful Improvements in Fuse-Igniters, of which the following is a specification.

This invention contemplates an improvement over my fuse igniter, described and 10 claimed in my co-pending application, filed Apl. 26, 1909, Serial Number 492,874.

It has for its object to provide for the instantaneous ignition of the powder in the powder duct of a fuse, and to preserve the 15 fuse ends against moisture, and the lighted fuses against extinguishment.

Another object of this invention is to provide a means for instantly communicating ignition to the powder in a fuse, which 20 means is unaffected by mine-drippings or water, and which is highly economical on account of the cheap material from which the present igniter may be manufactured.

These and other objects are accomplished 25 by the embodiment of the invention in the various forms illustrated in the accompanying drawings, in which,

Figure 1, is an elevation, partly in section, showing a tubular igniter provided with a 30 rubber sheath. Fig. 2, is a side elevation of the same, showing the rubber sheath unfurled and extended over the joint between the cap and the fuse.

Specific reference being had to the drawing, 35 1, designates a tubular body having a lighting tab 2, and 3 a powder charge within said cap and in proximity to said tab 2. Said tubular body consists of celluloid, colloidionized paper, or fibrous material, saturated or coated with a highly inflammable 40 substance, such as gun-cotton and the like, whereby the same is rendered quickly ignitable and at the same time insured against the action of the atmosphere and moisture.

By coating a paper or fibrous tubular body with a solution highly sensitive to heat, the combustion of the same after the ignition is retarded, while the heat is transmitted to the powder charge confined within 45 the tubular body. In this manner the tubular body forms a guide for the direction of the flame resulting from the combustion of the powder, and the heat is confined within

the walls of the body and carried down into the end of the fuse 4, for a considerable distance, while the fibrous tube or cap which is fitted over the end of the fuse remains intact for a small period of time, until the flame from the powder has been projected into the powder duct. The tab or apex of 55 the tube is, however, sufficiently susceptible to the action of direct heat to become ignited immediately upon the application of the same thereto, but in order to absolutely insure the speed ignition of the end of the 60 cap, I prefer to thin the tab. This invention therefore, is primarily directed toward the provision of a means for preventing the ingress of water at the joint between the bottom of the cap and the fuse. 65

To the cap 1, is attached one end of an elastic sheath or shield 4, which is rolled up on the tubular body and is arranged to remain in such rolled up condition until required for use. When the tubular body has 70 been placed upon the end of the fuse 5, the rolled up rubber or elastic sheath is unfurled until it covers the entire cap and a portion of the fuse, as seen in Fig. 2. In this condition, immersion in water or exposure to moisture will not affect the powder 75 in the fuse.

What I claim, is:

1. An igniter comprising a tubular body of inflammable material adapted to fit over 80 the free end of a fuse, a powder charge within said body, and a cover secured to said body and adapted to be unfolded longitudinally of said body to cover the joint between the body and the fuse. 85

2. An igniter adapted to be fitted over the free end of a fuse, comprising a tubular body having confined therein a powder charge, and an elastic covering on said body, said covering being arranged to be unfolded 90 and engage a portion of the fuse. 95

3. A tubular body of inflammable material adapted to fit over and form a seal for the free end of a fuse, said tubular body being provided with a foldable cover. 100

In testimony whereof I affix my signature in the presence of two witnesses.

HARRY BARGMAN.
